DESIGN FOR A COMBINED HAIR CURLER
AND BOBBY PIN CONTAINER

Margaret Wajdik, New York, N. Y.

Application October 8, 1947, Serial No. 141,804

Term of patent 7 years

(Cl D86.—10)

To all whom it may concern:

Be it known that I, Margaret Wajdik, a citizen of the United States of America, residing in New York city, county of New York, and State of New York, have invented a new, original, and ornamental Design for a Combined Hair Curler and Bobby Pin Container, of which the following is a specification, reference being had to the accompanying drawing, forming part thereof, wherein,

Figure 1 is a front elevational view of a combined hair curler and bobby pin container showing my new design.

Figure 2 is a front perspective view showing the hair curler and bobby pin container in separated position.

Figure 3 is a top plan view of the combined hair curler and bobby pin container shown in Figure 1.

The rear and sides of the combined hair curler and bobby pin container are identical in appearance to the front shown, except for the omission of the small securing member.

I claim:

The ornamental design for a combined hair curler and bobby pin container, substantially as shown and described.

MARGARET WAJDIK.
